UNITED STATES PATENT OFFICE.

JUNIUS ALLEN HOWE, OF NEW YORK, N. Y., ASSIGNEE TO JUNIUS JACK HOWE, OF NEW YORK, N. Y.

RECORDING-REGISTER.

1,251,889.

Specification of Letters Patent.

Patented Jan. 1, 1918.

Application filed February 24, 1917. Serial No. 150,639.

To all whom it may concern:

Be it known that I, JUNIUS ALLEN HOWE, a citizen of the United States, and a resident of the city, county, and State of New York, have invented a new and useful Improvement in Recording-Registers, of which the following is a specification.

The object of my invention is to provide a recording register which may be attached and applied to an automobile, and preferably to an automobile truck, to show the mileage traveled, the velocity at all times of travel, and the time the engine is running, so that it will be possible to tell from the record whether or not the vehicle is properly used. These, and other objects are accomplished by my invention, one embodiment of which is hereinafter more particularly set forth.

20 In the drawings, forming a part hereof, Figure 1 is a plan view of my improved recording register with the cover removed.

Fig. 2 is a sectional view taken on the line 2—2 of Fig. 1, looking in the direction of the arrows.

Fig. 3 shows a portion of the clock mechanism and the frame of the same.

Figs. 4, 5 and 6 are sectional views, taken on the lines 4—4, 5—5 and 6—6 respectively of Fig. 1.

Figs. 7 and 8 show a device on the reel for securing the record, Fig. 8 being a sectional view taken on the line 8—8 of Fig. 7, looking in the direction of the arrows.

Throughout the various views of the drawings, similar reference characters designate similar parts.

My improved recording register 1 is provided with any suitable case 2 of which only the bottom part is shown, the top part being removed so as to reveal the interior. The recording mechanism 3, which is placed in the case 2, is actuated by the shaft 4 which is adapted to be connected to any wheel in the conventional manner, just as a speedometer is ordinarily attached, and by a pair of wires 5 which are connected in series with any suitable circuit of the automobile which is energized only when the engine is running.

The wires 5 run to a pair of magnets 6 which are mounted in a casing 2 in any suitable way and above them is an armature 7 which is hung from a rod 8 that runs

through the coil spring 9 mounted on a suitable shelf 10, which is fixed to the case 2, and the upper end of this rod 8 is pivoted by connecting to the lever 8 and fulcrumed at 12 upon any suitable support 13 which may rise from the shelf 10, or any other fixed part of the apparatus, which is suitable. The free end of the lever 11 is provided with a pencil 14 which normally bears on the record 15, which will be described below, while this record is on guide 16 and before it is wound on a reel 17.

Enough has been said to show that when the magnets 6 are energized, the armature 7 is drawn to them and then the pencil 14 is drawn off of the record 15 and does not mark the same, and that means that as long as the engine is running, the pencil 14 does not mark the record 15, and it does mark this record at all other times. From this it is apparent that the presence of the mark of the pencil 14 on the record 15 indicates that the engine is not running, and the presence of such a mark indicates that the engine is running.

Another pencil 18 is always parallel to the pencil 14 (see Fig. 4) and is mounted in a crosshead 19 that runs in suitable guides 20 which are fixed to the casing 2 by means of a cap-screw 21, as is shown, or in any other suitable way. The guides 20 are slightly separated so as to receive between them a cam plate 22 in which is found a diagonally disposed slot 23 which also engages the crosshead 19 so as to slide the same in the guides 20. The cam plate 22 is mounted so as to reciprocate in suitable guides 24 extending from the shelf 10, or in any other suitable manner.

The lower face of the cam plate 22 has a pin 25 which runs in a corresponding cam groove 26 of the cam 27 which is mounted to rotate in suitable bearings 28 which extend from the base of the casing 2. This cam 27 is fixed to a worm gear 29 which meshes with a worm 30 which is fixed to the shaft 4 so that this worm gear 29 and the cam 27 are always driven with an angular movement and velocity corresponding to the travel of a wheel of the vehicle. The entire length of the cam groove 29 corresponds to a definite mileage, as two miles, so that each travel of the pencil 18 in one direction indicates one mile of movement. It will be understood that the shelf 10 is slotted as indi-

cated in dotted lines in Fig. 5 so as to permit the pin 25 to extend therethrough and reach the groove 26.

The reel 17 is mounted on a suitable shaft 31 which is driven by a clock mechanism 32 of the conventional kind. This clock mechanism may be wound by means of the usual arbor 33 which extends through the face plate 34 of this clock mechanism 32, in the usual manner. The reel 17 is mounted on a spider 35 and has a number of extending arms 36 which are bent to engage and hold a rim 37 which may be of any suitable kind. It is preferably made with a hinged part 38 which is normally held by a coil spring 39 which has one end secured to the part 38 and the other to a part of the spokes 36 and its free end is given a mortise joint and provided with spikes 40 which enter corresponding holes in the rim 37 to hold the record 15 at one end and hold it securely. The record passes over the guide 16 and is pressed against the same by a leaf spring 41 secured to the lower surface of the shelf 10 and the guide 16 has its extreme end open so as to receive and hold a roll 43 of the record 15 so that when the device is in use, the record 15 may be inserted in the form of a roll 43, with its outer end drawn to the spring 41 and against the guide 16 and placed as shown in Fig. 1 where it is held by the spikes 40 as above set forth. The clock mechanism is sufficient to run for any time desired, as twenty-four hours, and to avoid making the record 15 on too small a scale, it is preferable to have it go twice around the reel in twenty-four hours.

The record 15 is divided with a slight difference in spacing so that after 12 hours, when the reel takes the second layer, and the feed is therefore slightly increased, the spaces are accordingly increased. It is obvious that if the device were made to run for several days and a longer record 15 were used, the spaces would have to be accordingly increased at the end of each 12 hours to compensate for the increasing diameter due to the increasing number of layers on the reel.

In the preferred embodiment of my invention the longitudinal marks are placed to indicate the respective runs of the pencils 14 and 18 and between these runs the hours are indicated. The transverse markings indicate quarter hours. When the vehicle is not running the pencil 18 always makes a

mark parallel with the longitudinal marks on the record, and if the engine is not running at such a time the pencil makes the corresponding mark. If the engine is running no mark is made by the pencil 14 as the magnet 6 is then energized as above set forth. The line made by the pencil 14 is indicated by the character 44 and the mark made by the pencil 18 is indicated by the character 45. It will be noticed that the line 44 is interrupted and the line 45 is broken with parts running parallel to the longitudinal lines of the record and parts running at an angle thereto. It is apparent that as the rotation of the reel is uniform, the nearer this angle approaches 90 degrees, the greater the velocity of the vehicle when the record was made, and from the line 45 it is easy to tell the exact time when the vehicle was in motion, the velocity and the distance traveled, and from the line 44 the exact time the engine was at rest. The record is made from these pencils 14 and 18 when bearing against the record 15, as above described, while this record is still on the guide 16 and before it gets to the reel 17, so that the record can always be made when resting on a fixed and smooth surface and never on the moving surface of the reel. Once a day the record 15 may be readily removed from the apparatus and a new record 15 inserted, as above described, and at that time the clock may be wound. The casing 2 is secured to the vehicle in any suitable way, not shown, and is protected by means of a lock or any other suitable means, so that it cannot be tampered with when not in use without leaving evidence of such tampering.

While I have shown and described one embodiment of my invention, it is obvious that it is not restricted thereto but is broad enough to cover all structures that come within the scope of the annexed claim.

What I claim is:

In a device of the class described, a driving shaft, a worm on said shaft, a worm-gear meshing with said worm, a cam connected to said worm-gear, a pintle adapted to engage said cam, a plate connected to said pintle, guides for said plate, a diagonally disposed groove in said plate, guides and a pintle holder in said guides, whereby the movement of the slide makes a transverse movement of the pencil guide.

JUNIUS ALLEN HOWE.
